COMBINED ILLUMINABLE MAKE-UP MIRROR AND STAND

Matthew J. Rothman, Great Neck, N.Y., assignor to Rialto Products, Inc., New York, N.Y., a corporation of New York

Filed Apr. 13, 1965, Ser. No. 84,770

Term of patent 7 years

(Cl. D86—10)

FIG. 1

FIG. 3

FIG. 1 is a front perspective view of the combined illuminable make-up mirror and stand, showing my new design;

FIG. 2 is a rear perspective view of the combined illuminable make-up mirror and stand; and

FIG. 3 is a side elevational view of the combined illuminable make-up mirror and stand, with the mirror in tilted position.

I claim:

The ornamental design for a combined illuminable make-up mirror and stand, substantially as shown.
